20 Mr 2,974; Oct. 29, 1966, R 33,820
7 Claims. (Cl. 206—46)**ABSTRACT OF THE DISCLOSURE**

A needle package having a slide for retaining needles mounted for longitudinal reciprocation in an envelope having a longitudinal slot through which a tab on the rear of the slide extends for limiting the extent of movement of the slide.

The invention relates to a package for needles or the like, formed after the manner of a folder and comprising a front wall and a rear wall.

Packages of this kind are known and have always an open-out configuration. In these known packages, the needles are generally mounted on a sheet which is loosely located in the package or glued with one end to the inside of the package. In order to remove needles from the package or to re-insert needles into the package, the same must be opened by opening out one or more of its walls. After the extraction or re-insertion of the needle or the like, the package must again be closed. Hence, the extraction or the re-insertion of the needles or the like is rather complicated with known packages.

The invention has the object of providing a package for needles or the like, of the kind hereinbefore described, from which the needles or the like can be extracted easily, and into which the needles can be re-inserted equally easily.

According to the invention, this object is realized in a package for needles or the like in that the package comprises a slide carrying the needles or like objects, arranged longitudinally displaceably between the front and rear walls and adapted to be pulled out from the space between these walls and to be re-inserted thereinbetween, and comprises means limiting the movement of this slide both in the extracted and in the inserted positions.

In view of the construction of the package, for extracting needles or the like from the package or re-inserting them again into the same, it is only necessary to pull out the slide for the needles or like objects from between the front and rear walls, enabling the needles or the like to be withdrawn from the slide or re-inserted thereinto. For bringing the slide with the needles or the like back into the package, it is merely necessary to push it back into the space between the front and rear walls. The means limiting the movement of the slide prevent the slide from becoming disengaged from between the walls or from being inserted too deep between them.

For mounting the needles or like objects on the slide, according to the invention, the front side of the slide is provided with a sheet for inserting the needles or similar objects, which sheet may be made of coloured and lustrous paper.

According to the invention, the means for limiting the movement of the slide are formed preferably in that way that the rear wall of the package has a longitudinal slot, extending substantially from its bottom end substantially to its top end, and the slide has close to its bottom end a tongue engaging into this longitudinal slot of the rear wall. In this configuration, the limitation of the movement of the slide is effected in that the tongue, engaged into the slot of the rear wall of the package, abuts

2

against the upper end of the slot when the slide is removed or withdrawn, and against the lower end of the slot when the slide is pushed in.

According to a further feature of the invention, both the front wall and the rear wall of the package have on their upper edges recesses or cut-outs, which are in alignment. These recesses permit the top edge of the slide to be gripped and to be pulled out from the space between the front and rear walls of the package.

According to yet another feature of the invention, the front wall and the rear wall of the new package have, near their upper ends, each a hole, which are in alignment, and the slide has near its upper end also a hole which is in alignment with the other two holes in the front and rear walls, when the slide is in its inserted position. These holes make it possible to fix the slide between the front and rear walls of the package, for example by pushing a plug or the like through the holes.

Moreover, the new package has, as known per se, an opening in the front wall, and a transparent shell, protruding from the front wall, is arranged in this opening. Preferably, the front wall has not only one such opening, but two or more, which may be interconnected or separate and which contain interconnected or separate shells of transparent material arranged to protrude from the said front wall.

The opening or openings in the front wall, as well as the shell or shells mounted therein, have the object of rendering visible the needles or like objects mounted on the slide, when this slide is in its inserted position between the front and rear walls of the package. The arrangement, number and type of openings in the front wall and of the shell or shells arranged therein, is or are governed by the type and arrangement of needles or like objects mounted on the slide. In order to achieve an attractive appearance, the opening or openings and the shell or shells have preferably a shaped configuration such as is known in the art. For example, each opening may have the shape of an equilateral octagon, and the configuration and arrangement of each shell may correspond to that of a ground diamond.

The accompanying drawing shows, by way of example, an embodiment of a package for needles according to the invention. In the drawing:

FIG. 1 is a front elevation of the package with inserted slide;

FIG. 2 is a rear view of the package with inserted slide;

FIG. 3 is a front view of the package with extracted slide;

FIG. 4 is a rear view of the package with extracted slide;

FIG. 5 is a diagrammatical side elevation of the slide of the package.

The package is constructed after the manner of a folder and has a rectangular front wall 10 made of strong paper and an equally rectangular rear wall 11, also made of strong paper. The rear wall 11 consists of two halves 11a and 11b, each formed by a strip of paper which is connected with one of the longitudinal edges of the front wall 10. The strip 11a has at its top and bottom end a projecting portion 12 and 13, respectively, which portions overlap the other strip 11b. By means of these projecting portions 12, 13, the two paper strips 11a, 11b, forming the rear wall 11, are glued together. The two mutually facing longitudinal edges of the two strips 11a, 11b are spaced from each other, thus forming a longitudinal slot 14 in the rear wall 11, extending between the projecting portions 12 and 13.

The front wall 10 of the package has two interconnected openings 15, 16 in the form of two superimposed equilateral octagons. In these openings 15, 16 are arranged two interconnected shells 17, 18 of a transparent synthetic

resin. The arrangement of these shells 17, 18 is such that they bulge out in front of the front wall 10 and are fixed with their edges on the reverse side of this front wall. The arcuate portion of the shells 17, 18 is defined by a number of faces, forming angles with each other, and the arrangement and dimensions of these defining surfaces are such that the arcuate portion of each shell 17, 18 has the shape of a ground diamond.

In addition thereto, the package contains a slide 19, located longitudinally displaceable between the front and rear walls 10 and 11 of the package, and adapted to be pulled out of, and pushed into, the space between the two walls 11 and 10. The slide 19 is made from strong paper and has a rectangular shape of dimensions corresponding to those of the walls 10 and 11. At some distance from its lower end, the slide 19 is equipped with a centre tongue 20 extending in the transverse direction, and formed by an incision. This tongue 20 extends through the longitudinal slot 14 of the rear wall 11 and is in engagement therewith.

A sheet of comparatively thin, coloured and lustrous paper 21 is glued to the front face of the slide 19. The arrangement of this sheet of paper 21 on the slide 19 is such that parts 21a, 21b and 21c thereof overlap and the parts 21b and 21c can therefore be bent upwardly. In addition, the part 21a of the sheet 21, glued directly to the slide, as well as the bendable parts 21b and 21c are provided with lateral ribs 21d. Three groups of needles 22 are pushed through these transversal ribs 21d, extending in the longitudinal direction of the package.

The front wall 10 of the package has at its top edge a substantially semicircular recess 23. The rear wall 11 of the package has at its top edge a corresponding recess 24 of the same shape and dimensions. In the zone of these recesses 23, 24, the slide 19 is accessible, in order to be pulled out of the space between the walls 10 and 11.

In addition, the front wall 10 and rear wall 11 of the package have, near the upper edge, each a hole 25, 26. These holes have the same dimensions and are in alignment. The slide 19 has a similar hole 27 near its upper edge. This hole 27 has the same dimensions as the holes 25, 26 and is so arranged that it is in alignment with these holes 25, 26, when the slide 19 is pushed down into the space between the walls 10 and 11. A plug or the like may be inserted through these holes 25, 26, 27, in order to fix the slide 19 between the walls 10 and 11.

If a needle 22 is to be extracted from the package or to be replaced in the same, the slide 19 is pulled out from between the walls 10, 11. The tongue 20 of the slide 19 slides within the longitudinal slot 14 of the rear wall 11, until it abuts against the projection 12 of the strip 11a of the rear wall 11. This abutment prevents the slide 19 from being fully withdrawn from the walls 10, 11. After a needle 22 has been extracted from the withdrawn slide 19 or replaced in the same, the slide 19 can again be pushed back into the space within the walls 10, 11. During this movement, the tongue 20 slides along the slot 14 of the rear

wall 11 in the opposite direction, until it comes to rest against the projection of the strip 11a of the rear wall 11. This abutment limits the inserting movement of the slide 19.

5. What I claim is:

1. A package for needles having a substantially flat folder like sleeve with a front wall and a rear wall, a plurality of needles mounted on a slide received in said sleeve for longitudinal displacement between said front and rear walls so as to be movable between an extended position wherein it extends from the sleeve and a retracted position wherein it is substantially enclosed, locking means for limiting the movement of the slide both in the extended and in the retracted positions, said locking means comprising a slot in the sleeve extending substantially from its lower end to its upper end and a tongue extending from the slide engaging said slot.

2. A package as claimed in claim 1, wherein said needles are mounted on a sheet attached to the front side of the slide.

20 3. A package as claimed in claim 2, wherein the rear wall of the sleeve is comprised of first and second halves with one half being connected to the other half by upper and lower projecting portions so that said slot is provided between said halves and said projecting portions.

25 4. A package as claimed in claim 3, wherein the front and rear walls of the sleeve have each a recess in their upper edges, and wherein these recesses are aligned.

30 5. A package as claimed in claim 3, wherein the front and rear walls of the sleeve have near their top edge holes which are in alignment with each other, and the slide has near its top edge a corresponding hole which is in alignment with the said holes of the sleeve, when the slide is in its retracted position.

35 6. A package as claimed in claim 3, wherein the front wall of the sleeve has an opening in which is arranged a projecting shell of transparent material.

40 7. A package as claimed in claim 3, wherein the front wall of the sleeve has two openings in which are arranged shells of transparent material projecting from the surface of the front wall.
